FITZ WILLIAM SARGENT, OF MAHWAH, NEW JERSEY, ASSIGNOR TO AMERICAN BRAKE SHOE & FOUNDRY COMPANY, OF MAHWAH, NEW JERSEY, A CORPORATION OF NEW JERSEY.

REINFORCING-BACK FOR BRAKE-SHOES.

1,158,564.

Specification of Letters Patent. Patented Nov. 2, 1915.

Application filed September 13, 1915. Serial No. 50,355.

To all whom it may concern:

Be it known that I, FITZ WILLIAM SARGENT, a citizen of the United States, and a resident of Mahwah, in the county of Bergen and State of New Jersey, have made and invented certain new and useful Improvements in Reinforcing-Backs for Brake-Shoes, of which the following is a specification.

10 This invention relates to reinforcing backs for brake shoes, and has for its object to provide improved means for preventing the straightening out and spreading of the reinforcing back, and the opening up of the lug, 15 should the body metal of the shoe, disposed directly beneath the lug, become fractured and broken.

A further object is to provide a tie-plate for brake shoe backs with outwardly looped 20 lugs, wherein the tie-plate is so secured to the back and upon opposite sides of the lug that it is not dependent upon the cast body metal of the shoe for its securement and anchorage.

25 A further object is to provide a reinforcing back having longitudinally extending openings therein, the same being of such extent as to terminate a considerable distance short of the lug portion of the back, and about the 30 adjacent end walls of these recesses are bent the extremities of a tie-plate, the overlapping of the ends of the tie-plate resulting in the most secure anchorage of the latter to the back, and, at the same time, not in any 35 way interfering with the attachment of the brake shoe to a brake head.

Other objects and advantages will appear as the description proceeds, wherein it is to be understood that changes in the precise 40 embodiment of my invention can be made within the scope of what is claimed, without departing from the spirit thereof.

The preferred embodiment of my invention is disclosed in the accompanying drawings, wherein:—

Figure 1 is a view in top plan of a blank, from which my improved reinforcing back is formed; Fig. 2 is a view in longitudinal vertical section of a reinforcing back embodying the characteristic features of my invention; Fig. 3 is a fragmental view, in perspective of the looped portion of the shoe, and clearly disclosing the manner in which the tie-plate is anchored to the reinforcing back upon opposite sides of the looped lug;

Fig. 4 is a view, in vertical central section of a brake shoe having my improved reinforcing back embodied therein; and Fig. 5 is a detailed view in perspective of the tie-plate.

Referring specifically to the several views, the blank, illustrated in Fig. 1, is formed from an oblong plate 10, the central and lug-forming portion 11 of which is provided with the spaced and symmetrically arranged openings 12, these openings being adapted to receive the shoe attaching key after the blank has been shaped to its final form. Located upon opposite sides of the lug portion 11 are the longitudinally extending openings 13, and into which the molten metal of the body of the shoe flows to thereby increase the anchorage therefor. These openings 13, are of limited extent and terminate short of the lug forming portion 11, so that the confronting end walls 14 of these openings are positioned remote from the side walls of the looped lug.

The blank is subjected to the action of suitable forming dies, by which it is curved in its length and the central and lug portion 11 is outwardly formed to present the integral and looped lug 15, the openings 12 in which define suitable key openings. The tie-plate 16 in the form of an elongated thin strip of metal, and approximating in width the width of the recesses 13, is positioned beneath and across the looped lug 15, and the ends 17 thereof are bent up and around the ends 14 of the recesses 13. In this manner, the tie-plate is rigidly and permanently anchored to the back and upon opposite sides of the lug, so that the back is held against spreading and the lug against opening up. The efficient anchorage of the tie-plate is, therefore, not dependent upon the cast metal 95 of the body of the shoe, so that the lug is held against opening up and the back against spreading regardless of the degree to which the body of the shoe becomes fractured or broken or the amount it has become 100 worn. The provision of a separate tie-plate allows it to be formed of material not necessarily the same as that used for the formation of the reinforcing back.

The reinforcing back, as thus constructed, 105 is placed in a mold, and the body metal 18 of the shoe cast thereon, with the result that the body metal lying directly beneath the open lug, is reinforced throughout by the tie-plate 16. Although the cast metal of 110

the body of the shoe may, to some extent, supplement the securement between the ends of the tie-plate, and the reinforcing back, the securement of the tie-plate is not dependent thereupon, as the overlapping extremities effectively accomplish this end. The position of the end walls 14 of the recesses 13 remote from the sides of the lug, prevent the interference of these overlapping ends of the tie-plate with the brake head.

What I claim is:—

- 15 1. A reinforcing back for brake shoes including a looped lug and provided with longitudinally extending recesses arranged to the sides of the lug, and a tie-plate extending beneath said lug with the ends thereof interlocking with the ends of the aforementioned recesses.
- 20 2. A reinforcing back for brake shoes including a looped lug and provided with longitudinally extending recesses, arranged upon opposite sides of said lug, and with the

confronting end walls thereof spaced a distance from the side walls of the lug, and a tie-plate extending beneath and across the said lug with the ends thereof extending into contact and interlocking with the confronting end walls of said recesses.

3. A brake shoe comprising a reinforcing back with a looped lug, said back provided with recesses arranged upon opposite sides of said lug with the adjacent ends thereof terminating a distance from the sides of said lug, a tie-plate projecting beneath and across the said lug with the ends thereof being bent into engagement and interlocking with the end walls of said recesses, and a body anchored to the said back and tie-plate.

Signed at Mahwah in the county of Bergen and State of New Jersey this 10th day of September A. D. 1915.

FITZ WILLIAM SARGENT.
